CLAIM

The ornamental design for the electronic smoke device, as shown and described.

DESCRIPTION

FIG. 1 is the perspective view of the electronic smoke device showing my new design;

FIG. 2 is the left side view thereof;

FIG. 3 is the right side view thereof;

FIG. 4 is the top plan view thereof;

FIG. 5 is the bottom plan view thereof;

FIG. 6 is the front elevational view thereof; and,

FIG. 7 is the rear elevational view thereof.

The broken lines in FIG. 5 depict parts of the electronic smoke device that form no part of the claimed design.
